(57) **CLAIM**

The ornamental design for an elastic textile, as shown and described.

DESCRIPTION

FIG. 1 is a perspective view of an elastic textile showing my new design;

FIG. 2 is a top plan view thereof;

FIG. 3 is a bottom plan view thereof;

FIG. 4 is a front elevational view thereof shown in cross section taken along lines 4-4 of FIG. 1;

FIG. 5 is a rear elevational view thereof shown in cross section taken along lines 5-5 of FIG. 1;

FIG. 6 is a left side elevational view thereof shown in cross section taken along lines 6-6 of FIG. 1; and,

FIG. 7 is a right side elevational view thereof shown in cross section taken along lines 7-7 of FIG. 1.

In the figures, the broken lines surrounding the perimeter define the bounds of the claimed design and form no part thereof.
